Primary Examiner — David G Muller*Assistant Examiner* — Nathan M Johnston(74) *Attorney, Agent, or Firm* — Muncey, Geissler, Olds & Lowe, P.C.(57) **CLAIM**

We claim the ornamental design for a vise, as shown and described.

DESCRIPTION

FIG. 1 is a perspective view of a vise showing our new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view.

The broken lines in the drawings illustrate portions of the

vise which form no part of the claimed design.

The dot-dashed line in the figures defines the boundary of claimed and unclaimed objects, and the dot-dashed line forms no part of the claimed design.
